UNITED STATES PATENT OFFICE.

NATHANIEL B. CREGIER, OF LOS ANGELES, CALIFORNIA.

DESIGN FOR A COMBINED DINING-TABLE SIGNAL AND RECEPTACLE FOR ARTICLES.

49,643.

Specification for Design.

Patented Sept. 12, 1916.

Application filed July 11, 1916. Serial No. 108,753. Term of patent 3½ years.

To all whom it may concern:

Be it known that I, NATHANIEL B. CREGIER, a citizen of the United States, residing at Los Angeles, in the county of Los Angeles and State of California, have invented a new, original, and ornamental Design for a Combined Dining-Table Signal and Receptacle for Articles, of which the following is a specification, reference being had to the accompanying drawing, forming part thereof.

Figure 1 is a side view. Fig. 2 is a plan view.

I claim:

The ornamental design for combined dining table signal and receptacle for articles, as shown.

NATHANIEL B. CREGIER.

Witnesses:

E. L. WALLACE,
MARGUERITE BATES.
